UNITED STATES PATENT OFFICE

153,827

DESIGN FOR AN EXTENSIBLE WATCH
BRACELET

Charles Schaeffer, Cleveland, Ohio, assignor, by mesne assignments, to John Major, Chicago,
Ill., and Hans J. Duester, Norwood Park Station,
Chicago, Ill.

Application September 18, 1947, Serial No. 141,464

Term of patent 14 years

(Cl. D45—4)

To all whom it may concern:

Be it known that I, Charles Schaeffer, a citizen of the United States, residing at Cleveland, county of Cuyahoga, and State of Ohio, have invented a new, original, and ornamental Design for an Extensible Watch Bracelet, of which the following is a specification, reference being had to the accompanying drawing, forming a part thereof.

Fig. 1 is a top plan view of an extensible watch bracelet, showing my new design;

Fig. 2 is a side elevational view of the bracelet;

Fig. 3 is a view, on a greatly enlarged scale, of a portion of the bracelet shown in Fig. 1;

Fig. 4 is a fragmentary cross-sectional view, taken on the line 4—4 of Fig. 3, and

Fig. 5 is a fragmentary cross-sectional view, taken on the line 5—5 of Fig. 3.

The characteristic features of my design for an extensible watch bracelet, reside in the portions shown in full lines with the conventional end hooks shown in broken lines, the portions shown in full lines being repeated throughout the length of the bracelet as indicated by the dot and dash lines across the center of Figs. 1 and 2.

I claim:

The ornamental design for an extensible watch bracelet, substantially as shown and described.

CHARLES SCHAEFFER.
